D15-132.

OR D12,839

EX

Design No. 12,839, dated March 28, 1862.

UNITED STATES PATENT OFFICE

VERNON F. PRENTICE, OF WORCESTER, MASSACHUSETTS.

DESIGN FOR AN UPRIGHT DRILLING MACHINE.

SPECIFICATION forming part of Design No. 12,839, dated March 28, 1882.

Application filed January 23, 1882. Term of patent 14 years.

To all whom it may concern:

Be it known that I, VERNON F. PRENTICE, of Worcester, in the county of Worcester and State of Massachusetts, have invented and produced a certain new and original Design for Upright Drilling Machines; and I declare the following to be a description of my said design, sufficiently full, clear, and exact to enable others skilled in the art to which it appertains to make and use the same, reference being had to the accompanying drawing, which forms a part of this specification, and which represents a perspective view of a drilling-machine conforming to my new design.

The principal feature in my design is the peculiar form and proportions of the frame and the relative location thereon of the several operative parts to give a vigorous, graceful, and pleasing appearance to the machine.

a is the main cylindrical column, with its foot resting upon the elongated base-plate *b*, and having along its forward part, above the cylindrical bearing of the table *c*, the vertical dovetailed guideway *a'* for the working-head *e*, while at the rear, and at a short distance away from said main column *a*, is the back standard, *d*, of elliptical sectional form, and standing parallel to said main column for a length corresponding to the length of the guideway, or nearly so, and connected to the rear of the main column *a* by the transom-bars *d'* at the upper and lower extremities of the straight portion, as indicated. The lower portion of the back standard is divided to form two portions or limbs, *g* and *h*, that curve away from each other sufficiently to include the cone-pulley *i* of the counter and then descend and rest upon the bed-plate *b*, as shown, the bearings for the counter-shaft being on said parts *g* and *h*, near the bed-plate, and the driving-pulleys *i'* located in rear of the limb *h*. An inclined cross bar or brace connects the curved portions of the limbs *g* and *h* above the cone *i*. The

top of the frame is made with a forward-arched portion, *a²*, as a continuation of the cylindrical column *a*, which terminates with the upright bearing *a³*, that guides the drill-spindle and forms the seat for the spindle-operating gear above and cone-pulleys *j* below, relatively located as shown. An arm, *m*, springs from above the back standard, *d*, with an outward and upward curve, as shown, for sustaining the rear bearing of the operating-shaft. The lower part of arm *m* broadens out to meet the arched portion *a²*, with a central upright, *l*, springing from their junction and rising to carry the center bearing of the operating-shaft, the cone pulleys *k* and speed-gears being located in the space between the arms *m* and *l*, as illustrated. The front bearing, *n*, stands upon the top of the arch *a²*.

This design imparts to the drilling machine graceful proportions, vigorous form, and a very pleasing and desirable ornamental appearance.

What I claim, and desire to secure by Letters Patent, is—

1. The design for an upright drilling machine hereinbefore described, the same consisting of the upright portions *a* *a'* *d*, divided rear foot, *g* *h*, and top portion composed of the forward arch, *a²*, arm *l*, and rear arm, *m*, formed and relatively disposed as shown.

2. The design for an upright drilling machine, the same consisting of the uprights *a* *a'* *d*, divided supports *g* *h*, resting on the bed *b*, forward arch, *a²*, and rear arm, *m*, respectively formed and proportioned as shown, with the several operative mechanisms located and disposed in relation thereto in the manner illustrated and described.

Witness my hand this 10th day of January, A. D. 1882.

VERNON F. PRENTICE.
